UNITED STATES PATENT OFFICE.

CHARLES MATHER, OF PASSAIC, NEW JERSEY.

HANGER.

1,091,942.

Specification of Letters Patent. Patented Mar. 31, 1914.

Application filed April 8, 1913. Serial No. 759,734.

To all whom it may concern:

Be it known that I, CHARLES MATHER, a citizen of the United States, and a resident of Passaic, county of Passaic, and State of New Jersey, have invented certain new and useful Improvements in Hangers, of which the following is a full, clear, and exact description.

This invention relates more particularly to a hanger adapted to support electric cables which are placed in conduits.

Conduits for large underground electric cables have a number of openings for a number of independent cables and these conduits at different points are intercepted by man-holes in order that the conduits at intervals may be accessible to the cables. The man-holes are usually of considerable size and in passing across the man-holes the cables have to be supported. It is usual in such instances to provide a hanger or rack which may support one or sometimes as many as three or more of such cables. Heretofore, so far as I am aware, the hangers in use have recessed portions forming seats for different cables but such hangers do not permit various adjustments to properly support the cables, and further, the hangers are so supported that they cannot be held in the desired compact relation with respect to each other and while in such relation attached to or detached from a support.

The principle object of the present invention is to overcome the objections referred to and to provide a simple and efficient hanger or device by which one or more cables may be properly supported and permitted to assume various angles to adapt the cable in passing across a man-hole through one of the individual tubes to enter another one not necessarily in alignment therewith if the tubes are so positioned with relation to each other.

Another object of the invention is to provide a simple and efficient hanger or device which will not require more space for its attachment or detachment to a support than substantially the actual size of the hanger itself in order that a number of the said hangers may be superposed to adapt a large number of cables to be supported.

A further object of the invention is to provide simple and efficient means for properly holding the hanger to a support.

A still further object of the invention is to

provide a hanger which may be used for various purposes and in various connections.

With these and other objects in view, the invention will be hereinafter more particularly described with reference to the accompanying drawings, which form a part of this specification, and will then be pointed out in the claims at the end of the description.

In the drawings, Figure 1 is a sectional plan view through a man-hole showing one form of the invention in use and supporting two electric cables. Fig. 2 is a vertical section, partly in elevation, on a large scale, showing how the hanger is held to a standard or support. Fig. 3 is a front elevation, a part of the standard or support being broken away; and Fig. 4 is a detail perspective view of the hanger.

A number of man-holes 10 are arranged at intervals along the conduit for electric cables and within said man-holes are placed a number of supports or standards 11. These standards or supports 11 may be of channel iron and may be built as a part of the man-holes, which latter may be of cement, brick, or other material. Each standard or support 11 has a plurality of slots or openings 12 arranged above each other and substantially central of said support. Each slot 12 has a small or narrow part 13 and a transverse grooved part or broad portion 14 forming substantially an inverted T-shaped slot which is adapted to be engaged by the head 15 of a spring 16. The spring 16 is held at one end by one or more rivets 17 or other fastening means to a bracket, arm or member 18 and within an arch-shaped part 19 of said bracket. The bracket 18 may be of any suitable material and of any desired length and either or both ends may be closed, as at 20. The end 20 has a slot 21 to permit the head of the spring 16 to project therethrough beyond the end. This head 15 is somewhat larger than the shank or body of the spring and is of a size to fit the groove or broad portion 14 of the slot 12 and the small part or shank of the spring is of a size to fit the narrow portion 13 of the slot.

The bracket 18 is placed in position and held to the support 11 by causing the head 15 of the spring 16 to enter the groove 14 of any one of the slots 12 and permitting the smaller part of the spring to enter the part 13 of the slot which will serve to lock the bracket 18 to the support, the end 20 at this

time resting against the face of said support. The spring or member 16 may be normally forced away from the arched part 19 of the body of the bracket by inserting a tool, pencil or instrument of any kind through an opening 22, by which the spring 16 may be forced far enough to cause the head 15 to be passed through the slot 14 and then by releasing the spring the latter will shift to a position to cause the ends of the head 15 to be locked to the support. The bracket 18 is also provided at the lower end of the end 20 with a lug or projection 23 which is adapted to enter one of the slots 12 beneath the one through which passes the locking head 15, thus serving further to support the bracket 18 properly and detachably to the support 11. By this means, the bracket 18 may be held to or detached from the support by simply pressing on the spring 16 through the opening 22 and without disturbing in any way the cables above or below the same so long as there is sufficient space simply for the arm or member 18 to be moved endwise in position, thus the cables may be held in a very compact relation.

To support the cables and to adapt the same to be properly positioned with respect to the bracket 18, I provide a cradle or member 24. This cradle may be of porcelain or any other suitable material and is curved or recessed to form a seat 25 for the cable, the cable being indicated in dotted lines at 26, in Figs. 2 and 3, and in full lines in Fig. 1. The cradle 24 rests upon the arch-shaped portion 19 of the bracket 18 and is recessed, as at 27, underneath the same to fit said arch-shaped portion and by which the said cradle or member may be moved about the arch 19 to adapt the cradles to extend at various angles through the man-holes 10. The arch or arch-shaped part 19 is of sufficient length to support several of the cradles 24 and these cradles are adjustable lengthwise to properly position the same along the bracket as well as angularly. Each cradle 24 has a groove 28 and a rib or tongue 29 along two sides thereof and the rib 29 of each side is adapted to fit into a groove 30 extending lengthwise of the bracket or member 18. The bracket 18 is provided with a rib 31 adjacent to each groove 30 and on opposite sides thereof and either rib 31 is adapted to fit into one of the grooves 28 of the cradle. The purpose of the tongue and groove of the cradle and of the bracket 18 is to permit the cradle to be adjusted about the arch 19, and should the angular adjustment be such as to cause the tongues and grooves of the cradle and member 18 to en-

gage each other, it will prevent the cradle 24 from becoming entirely disengaged or falling from the arch as the said cradle is free to move about said arch. The cradle is thus supported in such a way as to permit adjustment lengthwise to position the cradle with respect to the cable and the cradle also is permitted to be adjusted laterally about the arch 19 to compensate for any desired angle or inclination of the cable.

From the foregoing, it will be seen that a simple and efficient hanger or supporting means for electric cables or other purpose is provided; that said hanger may be readily attached to or detached from a support; that said hanger or device requires no more room for its attachment or detachment than substantially the actual size of the device; that simple means is provided for permitting the cable to assume various angles or inclinations without liability of injury thereto; and that said device is simple in construction and inexpensive to manufacture.

Having thus described my invention, I claim as new and desire to secure by Letters Patent:—

1. The combination of a support, a bracket having an arched body and a tongue and groove along each edge lengthwise thereof, and a cradle of insulating material having a recessed portion forming a seat for a cable and having a tongue and groove along each edge adapted to engage the tongue and groove of said bracket and to be freely movable lengthwise of the bracket and laterally about the arched body thereof.

2. In a hanger, a bracket having an arched body and a tongue and groove along each edge lengthwise thereof, and a cradle having a recessed portion forming a seat for a cable and having a tongue and groove along each edge adapted to engage the tongue and groove of said bracket and to be freely movable lengthwise and about the arched body.

3. The combination of a support, a hanger bracket, and an independent supporting member adjustable to different inclinations around said bracket.

4. In a hanger, the combination of a bracket having an arch-shaped body adapted for attachment to a support, and a cradle freely movable to different inclinations around said arch-shaped body.

This specification signed and witnessed this 5th day of April A. D. 1913.

CHARLES MATHER.
